6 Claims. (Cl. 178—69.5)

The present invention relates to television systems and has primarily been devised to provide a "time base" whereby a facsimile of the raster of a transmitter can be synchronously reproduced in receivers.

In television reception, it is well known that major difficulties arise in the performance of scanning operations which are detrimental to faithful reproduction of a facsimile of the raster at the transmitter and according to known practice it is usual to transmit a synchronising signal to determine the starting times for the lines of the raster.

During the time occupied in transmission of said synchronising signal, no picture elements are being recreated thus resulting in a relative loss of brilliancy of the recreated pictures since the recreation of the pictures does not occur during the whole time that pictures are being viewed, and further, while said signal controls the starting times i. e. the location at the start for the lines of the raster it does not prevent drift displacement of the required trace of the cathode ray.

Further, the said synchronising signal is impressed upon a carrier frequency which latter is subject to atmospheric and other interferences which tend to mutilate or mar the raster and upset the precise timing of the lines of the raster.

In addition the transmitting apparatus is unduly complicated by the inclusion therein of means for generating, amplifying and transmitting the said synchronising signal and the apparatus at the receiver is also complicated by the necessary means for separating out and amplifying said signal.

According to the present invention the above disadvantages are avoided and the stated objective attained by applying to the control grid circuit of saw tooth oscillators at the transmitter and at the receiver which oscillators generate saw tooth potentials applied to deflecting electrodes of a cathode ray tube for imparting frame and line sweep movements to cathode rays used for scanning, similarly phased pulses of potential derived from E. M. F. of periodically varying amplitude and having similar characteristics, whereby the changes in said saw tooth potentials are synchronised, said pulses being derived from a source of alternating current at the transmitter and receiver.

In practising the invention saw tooth oscillators will be included in the transmitter and receiver the periodicity of the oscillations produced thereby being synchronously controlled by the 55

beforementioned phased pulses. At the receiver a phase splitter or the like is employed to adjust and synchronise oscillations therat with those at the transmitter. The oscillations first above-mentioned may be generated by a condenser in series with a resistance and discharging said condenser by means of a thermionic discharging valve shunted across the latter. Means are provided to apply negative potential across the grid of the discharging valve while the condenser is being charged.

In order to discharge said condenser a positive peaked form of pulse is applied to the grid of said valve. Said positive form of pulse is obtained by utilizing the positive pulses from the E. M. F. above specified which pulses may be used for the starting of peaked forms of pulses, the polarity of which latter is arranged to be positive, or preferably alternately positive and negative and applied to the grid of the discharging valve. Again an oscillator of the multi-vibrator type may be used to generate the saw-tooth oscillations as that type produces relatively stable oscillations and rapidity of fly-back, in which case a peaked form of pulse of either negative or positive polarity may be applied to the grid of one of the valves of the multi-vibrator unit.

In a preferred arrangement of the thermionic discharging valve which is shunted across a charging condenser, the peaked form of positive pulse is applied by a relatively small condenser to the grid of said valve, a relatively large resistance compared to the plate impedance of the valve connected to said grid being connected in series with a condenser connected to the cathode of said valve. The time constant of the last two mentioned condensers and the resistance connecting the same is preferably relatively small compared with the periodicity time of the said positive pulse so that the peaked pulses of potential applied to these components may be more sharply peaked.

By this preferred arrangement the potential of the charging condenser is raised to a maximum since during the time that the said positive pulse is applied to the grid, the charging condenser is discharged, also grid current flows, thus negatively charging the said relatively small condenser connected to the grid and this charge holds the grid negative while the charging condenser is being charged thus enabling the potential of the charging condenser to be raised a relatively large amount.

The accompanying schematic diagrams marked Fig. 1, Fig. 2, Fig. 3 and Fig. 4 depict circuit ar-

rangements adapted for utilizing the present invention.

In the circuit arrangement in Figure 1 the phase splitter comprises variable condenser C1, potentiometer R1 and R2.

Potentiometer R1 and condenser C1 are adjustable to vary the phase angle between the potential across 1 and 2 and the potential across the resistances of R1 and R2.

The potential applied across 1 and 2 consists of pulses of potential derived from E. M. F. of varying amplitude as before stated.

The variable arm of potentiometer R2 is connected to the grid 3 of the first stage tube V1 so that the signal potential applied thereto may be varied, the plate load of said tube comprising resistor R5 in parallel with potentiometer R4 shunted thereacross, R4 and R5 being also connected to the tapping point 4 on a potential divider PD comprising resistances R6 to R9 inclusive. R4 and R5 are shunted by condenser C13.

The plate 5 of tube V1 is connected through coupling condenser C2 with the grid 6 of tube V2 and a resistor R10 is also connected to said grid and to point 8 on potential divider PD.

The cathodes of tubes V1 and V2 are connected to each other and to point 8 on potential divider PD while an anode load resistor R11 is connected between plate 10 of tube V2 and point 9 on said potential divider.

Points 11 and 12 of the latter are connected respectively to the positive lead 13 and negative lead 14 of the high-tension D. C. supply for applying a steady potential to the plates of tubes V1 to V5 inclusive. Inductance L1 in the positive lead 13 is connected to point 11 and also to condenser C7 which latter is connected to said lead between point 11 and inductance L1 and to negative lead at 14.

Plate 10 of tube V2 is also coupled, via condenser C8 with the grid 15 of tube V3, R12 being a resistor connected to said grid and to the condenser C4 which latter is also connected to the negative lead 14.

The plate 17 of tube V3 is connected through condenser C5 to negative lead 14 and also to output lead 18, the latter and lead 18 being the outlet terminals for the saw tooth frame sweep potentials. Potentiometer R4 is connected through condenser C6 to grid 19 of valve V4. Plate 20 of valve V4 is connected by resistor R14 to positive lead 21 which latter is connected through inductance L2 to positive lead 13. Condenser C8 is connected on the plate side of L2 to negative lead 14.

Plate 20 of valve V4 is connected to output terminal 22 and the control grid 24 of valve V5 is connected to output terminal 23, the latter and terminal 22 being outlet terminals for line sweep potentials.

Resistor R15 is connected to grid 19 of valve V4 and to negative lead 14 and is shunted by condenser C14. Condenser C9 is connected from grid 19 of valve V4 to plate 25 of valve V5.

Resistor R16 is connected to plate 25 of valve V5 and to positive lead 21 and resistor R17 is connected from the latter to screen grid 26 of valve V5. Condenser C10 is connected from said screen grid 26 to negative lead 14. Condenser C11 is connected from plate 20 of valve V4 to control grid 24 of valve V5 and potentiometer R18 is connected from said control grid 24 to negative lead 14.

The valve V4 may be a pentode, screen grid or triode and valve V5 may be a pentode or screen

type of valve and the grid 27 may be connected to the grid 24 as shown in Fig. 1 or may be connected through a condenser or resistance to said grid 24.

5 Suppressor grid 27 of valve V5 is connected to control grid 24 of valve V5 but may be connected through a condenser or a resistance to said grid 24.

In operation with alternating current, potential is applied at points 1 and 2, the combination of components C1, R1 and R2 operating to vary the phase of the A. C. potential across R1 and R2 with respect to that across 1 and 2. Potentiometer R2 is used to vary the potential applied to grid 3 of first stage valve V1.

Said grid 3 of valve V1 is biased negatively to a relatively large extent so that when the alternating E. M. F. at 1 and 2 is changing to approximately maximum positive potential, i. e.

20 during a fraction of the time of its periodicity plate current flows in valve V1 causing equivalent amplified falling plate volts of valve V1 discharging condenser C2. The combined effect of the falling plate volts of valve V1 and the potential of condenser C2 causes an amplified negative

25 peaked transient potential to be applied to the grid 6 of valve V2, the product of capacity of condenser C2 and resistance of resistor R10 being predetermined to give a sharp peak to the said transient potential. Condenser C13 affords a bypass for high frequency currents in the plate load R4, R5. The grid 6 of valve V2 is biased to be at zero volts i. e. so that a suitable direct current plate current flows through said valve. The

30 amplified negative peaked transient potential applied to grid 6 of valve V2 causes the plate current of said valve to correspondingly decrease with amplified effect, thus causing its plate voltage to rise producing a corresponding positive transient

35 peak. The plate potential of valve V2 may be considered as made up of a direct current potential component and an approximately square topped form of fluctuating potential. The capacity of condensers C3 and C4 and of the resistance R12 are predetermined so that the approximately

40 square topped wave of plate potential of valve V2 and the corresponding potential of the latter and the corresponding potential drop across resistance R11 results in a wave of alternately positive and negative sharply peaked transient potentials between grid 15 of valve V3 and negative lead 14.

The resistance R12 is arranged to be relatively large compared to the plate resistance of valve V3 and size and capacity of condenser C4 is not critical but is preferably larger than condenser C3. When positive potential is impressed on grid 15 of valve V3 condenser C5 discharges through said valve and grid current also flows,

50 thus the plates of condenser C3 which are connected to said grid are charged negatively.

Further condenser C4 is charged to a small potential depending upon the size of its capacity and the resistance of R12. Negative potential of C3 on grid 15 of valve V3 prevents plate current flowing through the latter while condenser C5 is being charged. When the negative peaked

55 transient potential pulse is applied across C3, R12 and C4 the negative charge of condenser C3 is reduced by the discharge of condenser C4 and by leakage of the respective charges of said condensers i. e. the negative potential applied to grid 15 of valve V3 is slightly reduced to an amount

60 which is less than the potential of the charge given to it when the next positive transient pulse

is applied across C3, R12 and C4, but the potential of said negative charge is still great enough to prevent plate current flowing through valve V3. When the next transient positive pulse of potential is applied across C3, R12 and C4 the condenser C5 is discharged, grid current flows and the negative charge of condenser C3 is again increased to an amount corresponding to the positive potential of the transient pulse. Thus the grid 15 of valve V3 is held at a relatively high negative potential which is slightly less than the applied potential of the positive peaked transient pulses enabling the condenser C5 to be discharged on the application of the said last mentioned positive pulses and to be charged to a relatively higher potential than would be possible if either condenser C4 or resistance R12 was omitted.

The arrangement shown of C3, R12, C4 thus provides a convenient means for applying a relatively large negative potential to grid 15 during the charging of condenser C5. The use of peaked forms of transient potentials which are sharply peaked is advantageous in securing quicker cut off at charging and discharging of condenser C5.

In Fig. 1 the potential across condenser C5 is applied to the terminals 16 and 18 for the frame sweep potentials.

The direct current potential applied to negative lead 14 and positive lead 13, to supply power for the operation of the valves V1, V2 and V3, is relatively high compared to the potentials required across C3, R12 and C4 and the potentials for said power supply to valves V1 and V2 are obtained by the use of the potential divider PD the potential for valve V1 being obtained from tapping point 4 and the potential for V2 from point 9 of PD. The cathode bias for valves V1 and V2 is obtained from point 8 of PD enabling the use of the latter, with its separate connections for power supply to valves V1 and V2, to reduce unwanted oscillations, and, also the application of the relatively considerable negative potential bias to be applied to the grids of valve V1 as before mentioned.

The filter consisting of inductance L1 and condenser C7 provides for a smoother direct current potential to be applied across R13 and valve V3 and also to PD at points 11 and 12.

The multi-vibrator consisting of the valves V4 and V5 and components associated with the latter, is used for production of the line sweep potentials which may conveniently be taken across condenser C11. Potentiometer R18 may conveniently be used to vary the frequency of the line sweep potentials.

In the modified circuit arrangement in Fig. 2 amplifying valves V6 and V7 are located between the output leads 16 and 18 and valve V3. In addition, condenser C5a is connected in series with condenser C5 and to negative lead 14. Condenser C5b is connected between condensers C5 and C5a to grid 25 of valve V6 and grid leak resistance R19 is connected to said grid and to negative lead 14.

Plate 26 of valve V6 is connected to resistance R21 connected in series with potentiometer R20 to positive lead 13. Condenser C11 is connected to movable arm of potentiometer R20 and the grid 27 of valve V1. Grid leak resistance R22 is connected to said grid 27 and to negative lead 14. Resistance R24 is connected to plate 28 of valve V7 and to positive lead 13.

Cathodes 29 and 30 of valve V6 and V7 respectively are connected together and resistance R23

is connected to said cathodes and to negative lead 14 and is shunted by condenser C12. Output leads 16a and 18a are respectively connected to plates 27 and 28 of valves V1 and V6 respectively. Output leads 16a and 18a correspond to output terminals 16 and 18 in Fig. 1.

The valves V4 and V5 in Fig. 2 with their associated components constitute the oscillator for the line sweep potentials. It will be noted that valve V4 is shown as a pentode thus having a higher plate impedance than the triode valve V4 in Fig. 1 which is more suitable for giving higher frequencies to said potentials.

It will be noted that the amplifying valves V6 and V7 with associated components are connected together in paraphase, the connections of condenser C5 and C5a being arranged to act as a potential divider so as to reduce the amount of potential applied to grid 25 of valve V6.

The inclusion of the amplifying valves V6 and V7 provides a greater potential difference for a given potential drop across 13 and 14 and is arranged so that the output voltage at 16a and 18a shall be symmetrical about the earth potential of the cathode ray tube.

The potential applied to the grid 27 of valve V7 via the potentiometer R20 is preferably arranged to be equal to that applied to the grid 25 of valve V6. The time constant of resistance R19 and condenser C5b is preferably arranged to be approximately equal to the time constant of condensers C5a, C5 in series with resistance R13. By this preferred arrangement the preferred saw tooth form of potential is obtained across the output terminals of the leads 16a and 18a.

Referring now to Fig. 3 in the modified circuit arrangement shown therein valves V1 and V2 (shown in Figs. 1 and 2) and the components associated therewith are omitted and a potential from an alternating E. M. F. is applied to points 1c and 2c which correspond to 1 and 2 in Figs. 1 and 2. In Fig. 4 the suffixes 1b, 2b, 3b etc. correspond to suffixes 1, 2 and 3 etc. of Fig. 1 and components C1b, R1b, R2b etc. correspond to components C1, R1, R2 etc. in said Fig. 1.

In this modified arrangement sharply peaked potentials are not applied across condenser C3b, R12b, C4b but alternating potentials are applied which correspond to the alternating potentials applied to 1c and 2c. The output potentials of condenser C5b is arranged as before described in Fig. 1.

This modified arrangement operates to simplify circuit arrangements but as before stated the arrangement as in Fig. 1 whereby sharply peaked transient potentials are applied across grid 15 of valve V3 and negative lead 14, all things being equal is preferred, because for a given potential applied to positive lead 13 and negative lead 14 sharper changes in output potential and a relatively greater change of potential is obtained thereby.

Referring now to Fig. 3 the suffixes 1c, 2c, 3c etc. correspond to suffixes 1, 2, 3 etc. of Fig. 1, the modified arrangement in Fig. 3 is similar to that in Fig. 4 except that a diode valve V8 in series with potentiometer R26 is shunted across the movable arm of potentiometer R2c and negative lead 14c which latter correspond to 14 and 14b in Figs. 1 and 2 and 3 respectively. Condenser C3c, R12c and C4c are shunted across R26 between the movable arm of R26 and negative lead 14c.

This modified arrangement in Fig. 3 supplies an approximately square topped wave form of

potential across the potentiometer R26 which as above indicated is preferred to the arrangement shown in Fig. 3 in which latter a sinusoidal form of alternating potential may be applied across potentiometer R2b.

It will be readily appreciated that the frequency of the saw tooth sweep potentials, at output terminals at 16, 18 in Fig. 1 and the corresponding terminals in Figs. 2, 3 and 4 is the same as the frequency of the alternating potential pulses applied across terminals 1 and 2 in Fig. 1 and the terminals corresponding thereto in Figs. 2, 3 and 4.

I claim:

1. In television systems and for the purpose specified, generating means for creating saw tooth oscillations at the receiver and at the transmitter, means for adjusting the phase of said oscillations at the receiver, a source of E. M. F. of periodically varying amplitude and having similar characteristics at both the transmitter and receiver, means for applying pulses of potential derived from said E. M. F. to the control grid circuit of said generating means, means for applying the output of said generating means to the deflecting electrodes of a cathode ray tube for scanning at both the transmitter and receiver, said generating means comprising a condenser in series with a resistance, a thermionic valve shunted across said condenser and operating to charge the latter when a positive peaked form of aforesaid pulses is applied to the control grid of said valve, and means to apply negative potential to said grid while said condenser is being charged.

2. In television systems for the purpose specified, the combination of means specified in claim 1 and a multi-vibrator oscillator unit for generating said saw tooth oscillations to the control grid of one of the valves in which unit is applied said pulses of potential of either negative or positive polarity.

3. In a television system, an oscillator for generating saw tooth potentials applied to the deflecting electrodes of a cathode ray tube for imparting frame and sweep movements to the cathode rays used for scanning, comprising: means

for generating a substantially square topped wave of potential from a substantially sinusoidal wave potential, an electron discharge device having cathode, grid and anode, a resistance and capacity series circuit in which the resistance is large compared to the plate resistance of said electron discharge device, connected for applying waves of alternately positive and negative sharply peaked transient potentials derived from said first means between the grid and cathode of said electron discharge device for producing a saw tooth wave potential in the output of said electron discharge device.

4. Apparatus as set forth in the preceding claim 3 further comprising amplifying means having an input circuit, and coupling means consisting of a resistance and capacity circuit in the input of said amplifying means and a resistance capacity circuit in the output of said electron discharge device, said resistance capacity circuits having substantially the same time constants.

5. Apparatus as set forth in claim 3 in which the means for generating a substantially square topped wave potential from a substantially sinusoidal wave potential consists of a rectifier connected in series with a potentiometer and across a source of substantially sinusoidal wave potential supply.

6. In a television system, an oscillator for generating saw tooth potentials applied to the deflecting electrodes of a cathode ray tube for imparting frame and sweep movements to the cathode rays used for scanning, comprising: means for generating a substantially sinusoidal wave potential, an electron discharge device having cathode, grid and anode, a resistance and capacity series circuit in which the resistance is large compared to the plate resistance of said electron discharge device, connected for applying waves of alternately positive and negative sharply peaked transient potentials derived from said first means, between the grid and cathode of said electron discharge device for producing a saw tooth wave potential in the output of said electron discharge device.

I. L. MAGUIRE.
